US00D902620S

(12) **United States Design Patent** (10) **Patent No.:** **US D902,620 S**
(45) **Date of Patent:** **** Nov. 24, 2020**

(54) **SHEET PRODUCT DISPENSER**

(71) Applicant: **GPCP IP HOLDINGS LLC**, Atlanta, GA (US)

(72) Inventor: **Nathan Patrick Roche**, Atlanta, GA (US)

(73) Assignee: **GPCP IP HOLDINGS LLC**, Atlanta, GA (US)

(**) Term: **15 Years**

(21) Appl. No.: **29/685,235**

(22) Filed: **Mar. 27, 2019**

Related U.S. Application Data

(63) Continuation of application No. 29/604,055, filed on May 15, 2017, now Pat. No. Des. 850,145.

(57) **CLAIM**

The ornamental design for a sheet product dispenser, as shown and described.

DESCRIPTION

FIG. 1 is a perspective view of a sheet product dispenser in accordance with the present invention;

FIG. 2 is a front view of the sheet product dispenser of FIG. 1;

FIG. 3 is a rear view of the sheet product dispenser of FIG. 1;

FIG. 4 is a right side view of the sheet product dispenser of FIG. 1;

FIG. 5 is a left side view of the sheet product dispenser of FIG. 1;

FIG. 6 is a top view of the sheet product dispenser of FIG. 1; and,

FIG. 7 is a bottom view of the sheet product dispenser of FIG. 1.

(Continued)

The broken lines are included for the purpose of illustrating unclaimed features of the sheet product dispenser and form no part of the claimed design.

1 Claim, 6 Drawing Sheets
